TABLE TOP OR SIMILAR ARTICLE

Arthur Umanoff, New York, N. Y., assignor to Century Laminated Products Corp., Astoria, N. Y., a corporation of New York

Application April 1, 1955, Serial No. 35,326

Term of patent 14 years

(Cl. D33—14)

Fig. 1 is a top perspective view of a table top or similar article, both sides of the table top being the same in appearance; and

Fig. 2 is a cross-sectional view taken on line 2—2 of Fig. 1.

The dominant feature of my design resides in the specific configuration of the apron along each side as best illustrated in Fig. 1.

I claim:

The ornamental design for a table top or similar article, as shown and described.
